BUTTON LOOP

Application filed June 6, 1930. Serial No. 459,472.

This invention relates to button loops of the type having depending resilient arms having an attached member permitting a relative movable association with the depending arms.

The objects of the invention are to provide a two-part expansible button loop of which one part is adapted to be relatively moved out of the plane of the other part; to provide a two-part expansible button loop of which a contracted portion of one part is inexpansibly held by an axial pulling strain exerted upon the other part; to provide a two-part button loop of which one part is rigid and the other part is laterally expansible only upon the axially yielding bodily movement of the rigid part; and to provide a two-part button loop with integral connections adapting the manually forced bodily movement of one part to consequentially produce a movement of the other part in the plane of the button loop, but at right angles to the forced bodily movement. With these and other objects in view the invention consists in the novel constructions, to be hereinafter described or claimed, for carrying out the above stated objects and such other objects as hereinafter may be made to appear.

The character of the invention may be best understood by reference to one illustrative device embodying the novel features herein disclosed and illustrated by the accompanying drawings in which the Figure 1 is an elevation of the contracted button loop; the Figure 2 is a side elevation of the button loop with a part swung out of the plane of the other part; and the Figure 3 is an elevation of the expanded button loop, the Figure 4 illustrating a modified form by which both parts may be held in a common plane.

The device, as illustrated, comprises an improvement of the button loop disclosed by me in a separate application for Letters Patent of the United States executed this day and filed by me herewith, the improved device including the suspension loop 1, the button-receiving loop 2, the normally contracted throat portion 3, and the button-retaining loop 4, the loops 1, 2, and 4 being axially associated, each one with the others, in that

a vertical line (not illustrated) of one loop is the center line of each of the other loops. The improved device is made in two parts, one of which is of resilient wire of which a middle portion is bent to form the suspension loop 1, the other wire portions depending therefrom to provide the spring side arms 5 and 6 cooperating to provide the button-receiving loop 2 and the normally contracted throat portion 3, the wire extremities of the resilient part of the loop being provided with the loops 7 and 8 formed substantially in the plane of said part as illustrated by the Figure 1. The other part of the device is made of wire rigidly formed to provide the bar 9 having the seat 10 for the shank S of a button, and the relatively convergent elongated looped ends 11 and 12 formed substantially in the plane of said rigid part the outer portions 13 and 14 of which are engaged by the loops 7 and 8 of the resilient button loop part for a relative sliding movement between the button loop parts. Thus assembled the device is reversible in the sense that an elevation reversed to that illustrated by the Figure 1 would be substantially identical therewith.

When the shank S of a button rests within the seat 10 and is pulled axially of the button loop in a downward direction axial stress is placed against the bar 9, as illustrated by the Figure 1, and the rigidly formed part of the device is thereby bodily moved downwardly relative to the resilient part of the device, and the loops 7 and 8 are thus made to engage the upper portion of the relatively convergent looped ends 11 and 12, respectively, at which upper portion the distance between the relatively fixed loops of the rigid button loop part is the minimum, the engagement contracting the looped extremities 7 and 8 of the resilient button loop part, and hence the throat portion 3, the contracted condition of the button loop being maintained regardless of the spring tension of the arms 5 and 6 so long as the pulling stress is exerted upon the bar 9. Therefore should the tension of the arms 5 and 6 become insufficient to maintain a normally closed throat portion 3, that condition will be maintained by the relatively

high position of the loops 7 and 8 in engagement with the convergent looped ends 11 and 12. Upon the passing of the shank S through the throat portion 3, the throat portion is thereby forcibly expanded laterally as illustrated by the Figure 3. In order however that the throat portion 3 be permitted to so expand, the rigid member, comprising the bar 9 and the relatively fixed elongated converging loops 11 and 12, must bodily yield axially of the button loop toward the throat portion 3; for, as the looped extremities 7 and 8 of the resilient button loop part expand, the engagement of the extremities 7 and 8 with the upper portions of the fixedly spaced convergent loops 11 and 12 is released to permit the relative sliding movement of the resilient and rigid parts along the plane of the button loop that the expanded looped extremities 7 and 8 may assume positions of engagement with the lower portions of the fixedly spaced convergent loops 11 and 12, as illustrated by the Figure 3.

The Figure 4 illustrates a slight modification of the preferred structure of the button loop, the resilient part of the button loop having the loops 1, 2, and 4, the contracted throat portion 3, and the spring side arms 5 and 6, terminating in the looped extremities 7 and 8, respectively, while the rigid part of the button loop comprises the bar 9 having the seat 10 and supporting the fixedly spaced convergent loops 11 and 12 comprising in part the outer bars 13 and 14 respectively engaged by the extremity loops 7 and 8. The modification resides in providing the extremity loops 7 and 8 with the wire extensions 15 and 16, respectively, the extension 15 being made to closely engage against the structure of the loop 11 upon one side of the button loop plane, and the extension 16 made to closely engage against the structure of the loop 12 upon the opposite side of the button loop plane, the extremities 15 and 16 cooperating to maintain the button loop parts within a common plane.

I claim:

1. A two part expandable button loop, one part comprising, in part, an expandable button receiving loop having a normally contracted throat portion, and the other part comprising a button retaining loop axially associated with the expandable loop, and connections integrally provided substantially in a common plane by each of the parts, the connections including a pair of relatively convergent guides provided by one part and looped terminals provided by the other part and mounted upon said guides for a slidable and pivotal movement thereon to produce a relative axial bodily movement of the associated parts as the throat portion is laterally expanded and contracted.

2. A two-part expandable button loop, one part comprising, in part, a resilient wire but-

ton receiving loop having a contracting and expanding throat portion and terminals depending therefrom, and the other part comprising a button retaining loop member axially associated with the resilient loop, and connections integrally provided substantially in a common plane by each of the parts, the connections including a pair of upwardly convergent guides fixedly provided by the retaining member and looped terminals provided by the resilient loop and mounted upon said guides for a slidable and pivotal movement thereon to produce a relative axial bodily movement of the associated loops as the throat portion is laterally expanded and contracted.

3. A two-part expandable button loop, one part being of resilient wire structure providing a button receiving loop having a contractible and expansible throat portion and depending looped terminals, formed substantially in the plane of said resilient part, and the other part being a rigid wire loop structure axially associated with the resilient loop and providing elongated loops substantially in said plane fixedly spaced and relatively convergent, upon which the looped terminals of the resilient wire structure are slidably and pivotally mounted to permit the relative axial bodily movement of the associated parts on the expansion and contraction of the throat portion and the swinging of one part out of the plane of the other part.

4. A two-part expandable button loop, one part being of resilient wire structure providing a button receiving loop having an expandable and contractible throat portion and depending wire terminals looped substantially in the plane of the resilient part, the other part being of rigid structure providing fixedly spaced and relatively convergent guides substantially in said plane and slidably and pivotally secured to said looped terminals to permit the relative axial bodily movement of the button loop parts upon the expansion and contraction of the throat portion.

5. A two-part expandable button loop, one part being of resilient wire structure providing a button receiving loop having an expandable and contractible throat portion and depending wire terminals looped substantially in the plane of the resilient part, the other part being of rigid structure providing fixedly spaced terminals looped substantially in said plane and within the looped terminals of the resilient part, the looped terminals of one of the parts being elongated and relatively converging toward said throat portion.

JESSUP SALISBURY.
